(57) CLAIM

I claim the ornamental design for a sheathed battle rope, as shown and described.

DESCRIPTION

FIG. 1 is a top perspective view of the sheathed battle rope showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.

The broken lines shown in the drawings depict portions of the sheathed battle rope that form no part of the claimed design.
